PREPARATION OF ORIGINALS FOR REPRODUCTION BY PRINTING OR ANALOGOUS PROCESSES

Harold Vezey Strong, Ightham, and Rado Hagyi-Ristic, London, England

Application October 23, 1935, Serial No. 46,424
In Great Britain November 2, 1934

10 Claims. (Cl. 101—316)

This invention relates to the preparation of "originals" from which are reproduced by a suitable printing process sheets of printed matter, primarily but not exclusively sheets of music, the appropriate music signs and symbols or other characters or matter to be printed being impressed manually upon a sheet of paper, which in the case of an "original" for a music sheet bears the stave lines, by means of individual 5 stamps or dies the position of each of which is determined or located by a movable guide; and the invention has for its objects, to expedite the preparation of such "originals" and to enable them to be prepared accurately without demanding a high degree of manual skill such as is only 10 acquired by years of experience, to eliminate the necessity for engraving metal plates for the reproduction of printed music, and to simplify the process of producing music sheets by reducing 15 the number of steps to be performed.

While the invention is defined and described hereafter in particular relation to the preparation of printed music sheets, it is to be understood that its application is not limited thereto but may be extended to other printed matter, such for example as the insertion of place names or signs or symbols on maps or in other circumstances wherein the accurate location of letter press, 20 signs, symbols or characters in relation to a sheet serving as an "original" for a printed reproduction 25 is of paramount importance.

In the preparation of "originals" for printed sheets of music the location of a note sign or other symbol correctly in relation to the stave lines 30 is necessary, while the spacing correctly of the notes and symbols lengthwise of the stave and the sub-division of the stave into bars demands skill knowledge and execution on account of certain factors upon which the lay-out of the score depends, among which are the number of beats in 35 a bar and the respective values of the notes in each bar, both of which factors govern or influence the spacing of the notes in such a manner that a sheet of music shall present a correct musical "picture" to a person reading the music.

Firstly, according to the invention, the preparation of "originals" for the printed reproduction, primarily, of music, is effected by impressions on a sheet of paper obtained from individual stamps or dies, each of which is supported by a movable guide socket rigidly normal to the surface of the paper and which guide socket is provided with means to ensure that any symbol or sign shall be impressed on the paper in its correct relation to the stave lines. Thus the accurate positioning of a note sign, for example, whether on any given stave or leger line or between any given pair of stave or leger lines comprising the score, is determined.

Fundamentally, the spacing correctly of the

notes and symbols lengthwise of the stave is based on the mathematical sub-division of the length of a stave into units of space each of which bears a dimensional relationship to the width of a note symbol, preferably the head of a crotchet, that being the most commonly occurring symbol, (the maximum number of notes capable of being printed along a stave of given length without touching or overlapping being a known quantity) and the invention also extends to the 5 mechanical application of such mathematical sub-division in order to determine the correct spacing of the notes along a stave according to their respective musical values.

Secondly therefore, the invention also embodies 15 means whereby the aforesaid guide socket can be traversed intermittently lengthwise of a stave by selected numbers of units of space determined by the respective musical values and also the 20 number of the notes to be disposed along that stave. The extent of a unit of space is preferably less than the width of the head of a crotchet symbol, two or more such units being slightly 25 in excess of that width.

Preferably provision is made for an audible 25 or a visual indication, or both, of the extent of each note-spacing traverse imparted to the guide socket.

In its elementary form, for the location of a 30 note symbol on any given stave or leger line or between any given pair of stave or leger lines, the aforesaid guide socket, whereof the size and configuration are in one embodiment such as to fit closely against the shank of a stamp or die, 35 may be integral with or may have attached to it a datum edge or pointer so positioned on the guide socket that when said edge or pointer is aligned with a stave line the guide socket is located correctly to impress a note directly on that line.

A duplicate guide socket may also be employed 40 having a datum edge or pointer so disposed in relation to the guide socket that when aligned with a stave line the guide socket is located correctly to impress a note intermediately of that 45 stave line and the line next adjacent below it.

Alternatively, and preferably, instead of employing two separate guide sockets with differently positioned datum edges or pointers, a single 50 guide socket is formed with or has attached to it a stepped datum edge or pointer whereof one aligning edge is appropriate to the position corresponding to a note on a stave line and the other aligning edge is appropriate to the position corresponding to a note between the stave lines.

In another and more elaborate form of the invention, the guide socket may be mounted on a carriage slidably along a fixed or a movable 55 guide bar laid horizontally over a hard wood board or metal plate on which the paper bear- 60

- ing the stave lines to receive the necessary impressions is placed and which board or plate is also provided vertically with a fixed or movable guide bar along one edge or margin, or said board or plate may be traversable vertically in relation to a stationary base plate such as by rack and pinion mechanism; and the guide socket may be secured to a rack-rod or bar adapted to be moved, by means such as a knurled head, by amounts 5 each equivalent to half the distance separating adjacent stave or leger lines.

Alternatively, instead of being mounted on a rack bar, the guide socket may be serrated internally in correspondence with the stave lines 15 and the shank of the stamp or die may be tongued or notched or grooved in such a manner as it fits into said serrations.

In this form the guide socket may be serrated internally either along one or both sides. When 20 serrated along only one side, the guide socket may be mounted so as to be displaceable by an amount equivalent to half the distance separating adjacent stave lines.

When serrated along both sides, the serrations 25 are staggered by an amount equivalent to half the distance separating adjacent stave lines and the opposite sides of the shank of the stamp or die are so grooved, notched or tongued, that insertion of the stamp or die in one position into 30 the guide socket determines the location of an impression on a stave line while insertion of the stamp or die in the reverse position determines the location of an impression between adjacent stave lines.

35 Associated with the guide-socket or with the carriage on which it is mounted, there may be an adjustable index in order to facilitate the equal spacing of the impressions when that is necessary.

40 For the purpose of traversing the guide socket intermittently lengthwise of the stave, the guide socket and carriage are movable bodily along the aforesaid guide bar and the extent of each displacement of the carriage in order to effect the 45 spacing of an impression may be regulated by pawl and ratchet mechanism operated by a knurled head, or a lever, and wherein each tooth on the ratchet wheel corresponds to one of the aforesaid units of space the arrangement being 50 such that the selected number of units of space are set upon the pawl and ratchet mechanism the operation of which affords an audible indication of the number of units concerned and the mechanism being so constructed as to permit the 55 carriage to be slid along the guide bar only to the extent of the number of units of space for which the pawl and ratchet mechanism has been set.

As the length of the stave is not uniform for all 60 music sheets a scale of unit spaces is preferably provided and is applied to the stave in order to determine into how many unit spaces each stave can be sub-divided, and the number of unit spaces so ascertained is then divided by the number of 65 notes, symbols and signs to be disposed along a stave thus obtaining the average number, together with any surplus, of unit spaces allocatable to each note-symbol or sign.

To obtain the required musical "picture", however, 70 it will not be possible strictly to adhere to this average, owing to differences in the musical values of the notes, musical considerations necessitating the allocation some times of more and sometimes of less than the average number of 75 unit spaces to a note symbol or sign, and any

such departures from the average together with the above mentioned surplus, if any, are disposed of throughout the remainder of the stave as the work progresses; means being provided to indicate all such departures from the average together with any surplus for disposal. 5

According to the data so obtained the aforesaid pawl and ratchet mechanism can be operated in such manner as to apply the correct spacing to the impressions made along each stave. 10

Constructional embodiments of the invention are illustrated by way of example in the accompanying drawings in which:—

Fig. 1 is a top plan view of an elementary form of guide socket and an underside plan view 15 of one of its complementary die stamps bearing a note symbol.

Fig. 2 is a side view of the guide socket shown in Fig. 1, the die stamp, whereof the shank is broken away, being inserted therein. 20

Fig. 3 is a plan view of a complete apparatus, minus the die stamps, constructed according to the invention.

Fig. 4 is a sectional elevation on the line A, A, in Fig. 3, viewed in the direction of the arrows. 25

Fig. 5 is a sectional elevation on the line B, B, in Fig. 3, viewed in the direction of the arrows.

Fig. 6 is a sectional elevation on the line C, C, in Fig. 3, viewed in the direction of the arrows. 30

Fig. 7 is a side elevation viewed from the left hand of Fig. 3.

Fig. 8 is a front and Fig. 9 is a side view of 35 a die stamp for a single symbol, and Figs. 10 and 11 are similar views of a die stamp comprising a slug, while Figs. 12 and 13 are also similar views of a die stamp comprising separate type.

Fig. 14 is a plan view of a modified form of 40 guide socket and Fig. 15 is a side view and underside plan view of a complementary die stamp appropriate thereto, while Figs. 16 and 17 are similar views of a second modified form of guide socket and complementary die stamp. 45

Figs. 8 to 17, inclusive, are drawn to a larger scale than the preceding figures.

Referring firstly to Figs. 1 and 2, 1 is a metal tubular member of rectangular cross-section from one lower side of which projects horizontally a flat arm or blade 2 whereof the upper side is bevelled and is constructed with stepped datum or aligning edges 3 and 4 the distance between which is equivalent to half the distance 55 separating two adjacent music stave lines, and 5 is a steel or other suitable die stamp bearing at its lower end an appropriate note or other sign or symbol 6 in relief.

The die stamp 5 is adapted to be inked by any suitable means and to be applied to a sheet of paper bearing stave lines by first locating the tubular member or socket 1 in the desired position and with either the datum edge 3 or 4 coincident with one of the stave lines (according to whether the impression of the note is required on a stave or leger line or between two stave or leger lines) and then pressing the die stamp 5 manually through the socket 1, in which it is a good sliding fit, to apply the ink on the note symbol to the surface of the paper. 60

The size and configuration of the socket 1 and die stamp 5 are not limited to those illustrated but may vary, such for instance as to accommodate a die stamp bearing a succession 75

of notes or a number of letters forming a word or an abbreviation thereof.

The socket 1, whereof the under face is smooth, may be moved freely over the surface 5 of the paper to receive the impressions from any number of different die stamps such as 5, the accurate positioning of the note symbols on or between the stave or leger lines being determined by aligning either the datum edge 3 or 4 with a 10 stave line below that upon or those between which the particular impression is to be located.

In the more elaborate form of the invention illustrated in the Figs. 3 to 13 inclusive of the drawings the guide socket 1 is integral with, or 15 may be secured to a rack 7 provided on one side with teeth 7a with which there meshes a pinion 8 rotatable by means of a knurled head 9 supported by a carriage 10 relatively to which said 20 rack 7 is reciprocable. The rack 7 is provided on the side opposite to teeth 7a with further teeth 7b and the carriage 10 bears a catch spring 7c, a projection 7d of which is snapping in the space between two teeth 7b. The pitch of the teeth 7b is such that the extent of movement 25 imparted to the rack 7 by the movement of the pinion 8 through a distance of one tooth 7b is equivalent to half the distance separating two stave or leger lines, the carriage being provided with a rubber line and the rack-rod being provided with a series of lines representing stave 30 lines.

The carriage 10 is provided with a flanged base 11 slidably embracing a fixed guide bar 12 laid horizontally over a wooden base 13 upon 35 which said bar is supported by blocks 14, 14, and on the base 13 is disposed a hard wood or metal platen 15 capable of being traversed vertically of the base between fixed side rails 16, 16, the platen 15 being faced with a layer of rubber 17 40 on which is laid the sheet of paper 18 to receive the necessary impressions.

The lower edge of the guide bar 12 is formed with rack teeth 19 engaged by a pinion 20 supported by an extension 21 on carriage 10 and 45 rotatable by means of a knurled head 22 in order to traverse the carriage 10 along the guide bar 12.

In Figs. 3, 4, 5, 6 and 7, additional mechanism, to be described hereafter, is shown associated with the pinion 20, but at this stage such additional mechanism may be disregarded.

The sheet of paper 18 is held securely along its upper edge on the rubber facing 17 by means of a clamping bar 23 hinged at one end to a 55 forked bracket 24 fixed to the base 13 and having at its free end a loop 25 opposite the toe of an angularly movable arm 26 pivoted to a forked bracket 27 also fixed to the base 12.

Several examples of die stamps for insertion in 60 the guide socket 1 are illustrated in Figs. 8 to 13, inclusive, and each comprises a stem 28 of rectangular cross-section having a milled head 29, the lower extremity of the stem being bevelled or chamfered to facilitate the introduction of the 65 stem into the socket 1 wherein the stem is a good fit in order that it may be firmly supported while an impression is being made.

The stem 28 is integral with, or has secured to it, socket member 30 to receive the rectangular shank of the actual die stamp 31 which is held in the socket member 30 by the engagement with a groove 32 in the shank of said stamp of the nose of a latch member 33 pivoted at 34 to a forked lug 35 integral with the socket member 70 75 30, the latch member 33 being pressed into con-

tact through a slot 36 in the socket member 30, with the shank of the die stamp 31 by means of a curved spring 37 one end of which is anchored to a lug 38 upstanding from the socket member 30 and the other end of which bears against the 5 rear face of the upper end of the latch member 33.

In order to withdraw the stamp after it has been pressed through the socket 1 to make an impression on the paper, the socket 1 is provided with two abutment pins or pegs 39, 39, which 10 rest on springs such as 40 (Fig. 4) accommodated in apertures formed in the wall of the socket 1.

Instead of the above described socket 1 and its associated rack-rod 7 and pinion 8 and knurled head 9, and also instead of the above described 15 form of die stamp and holder, either of the modified constructions illustrated in Figs. 14 to 17, inclusive, may be employed.

In Fig. 14 there is shown an elongated die holder 41 adapted to be attached to the guide 20 bar 12 and which is slotted at 42 and serrated at each side of said slot 42 by means of two series of teeth 43, 44, spaced apart in correspondence with the stave lines of a music sheet, the teeth 44 being staggered in relation to the teeth 43 25 by an amount equivalent to half the distance separating adjacent stave lines.

Into the slot 42 there is adapted to be introduced the die stamp 45 whereof one side is formed with a rib 46 shaped to fit the grooves between 30 the teeth along the side of the slot 42 and the other side of the stamp 45 is formed with a pair of ribs 47, 47, similarly shaped to fit the grooves between the teeth bounding slot 42; the arrangement being such that insertion of the stamp 45 35 into groove 42 in one position will locate the impression from the stamp on a stave or leger line while insertion of the stamp 45 into groove 42 in the reverse position will locate the impression from the stamp between two stave or leger lines. 40

As shown in Fig. 16 the slotted die holder may be serrated at 43 along one side only of the groove 42 and the die stamp 45 may be formed with only a single rib 46.

In both these last described forms of die holder 45 the slotted and serrated part 41 is mounted so as to be displaceable lengthwise relatively to a plate or base 48 by an amount equivalent to half the distance separating adjacent stave lines.

For convenience of operation under some circumstances the platen 15 is arranged so as to be traversable upwardly of the base plate 13, as indicated by the arrow applied at the left hand side of Fig. 3, and for this purpose the platen 15 is rigidly connected to a rack-rod 49 which extends parallel with the left hand side of the platen and passes through a bearing bracket 50 screwed at 51 to the margin of the base 13 and formed with a bearing for a pinion 52 which meshes with the rack-rod 49 and is adapted to be rotated by 55 means of a knurled head 53, see Figs. 3, 4, 6 and 7.

It will be seen that by means of the mechanism hereinbefore described, the sheet of paper bearing music stave lines, represented by the dot and dash rectangular area 13 in Fig. 3, can firstly be 60 aligned correctly with the fixed guide bar 12, in order to bring that stave which is to receive note impressions into the correct position below the guide socket 1, by manipulating the knurled head 53, and by further manipulating the knurled 65 head 9 the guide socket can be adjusted so as to place the required impressions on or between the stave lines or leger lines lengthwise of which the carriage 10 can be traversed by turning the knurled head 22 in the required direction. If, 70 75

however, the apparatus is also to be capable of determining mechanically the subdivision of a stave for the purpose of ensuring the correct spacing of the notes therealong according to their 5 respective musical values, the following additional mechanism is provided.

On the arbor carrying the pinion 21 a ratchet wheel 54 is fast and is engaged by a detent 55 carried pivotally by an angularly movable lever 56 to which the tail of the detent 55 is anchored by a spring 57, said lever 56 being supported by the aforesaid extension 21 of the carriage 12 and having its forward or inner extremity located between a fixed stop 58 and an adjustable screw 15 stop 59 having a knurled head 60 and working in a bracket 61 springing from the carriage 12, the screw stop 59 being fitted with a knurled lock nut 62.

Normally the spring 57 tends to maintain the 20 nose of the detent 55 in engagement with the ratchet wheel 54 and an angularly movable arm 63 pivoted at 64 to the lever 56 is provided which may be pressed against the tail of the detent 55 to disengage the detent from the ratchet wheel 25 54 if and when desired.

Each tooth on the ratchet wheel 54 represents 30 one of the above mentioned units of space and by moving the lever 56 in a clockwise direction with respect to the knurled head 22 the detent 55 can be drawn peripherally of the ratchet wheel over any desired number of teeth in passing over each of which the pressure of spring 57 causes the detent to make an audible sound. Then by 35 moving the lever 56 in a counterclockwise direction with respect to the knurled head 22 the detent 55 causes the ratchet wheel 54 and with it the pinion 21 to rotate and by the latter's engagement with the rack teeth 19 on the guide bar 12 the carriage 10 is traversed a determined 40 amount lengthwise of the guide bar 12; the extent of this latter angular movement of the lever 56 being regulated by the adjustment of the stop 59.

The lever 56 may either be moved the full angular distance permitted by the stops 58 and 59, or it may be given a plurality of angular displacements each equal to the passage of the detent 55 over one or more teeth of the ratchet wheel 54.

50 Preferably means, not shown, are provided for affording on or in connection with the knurled head 22 a visual indication of the extent of each angular displacement of the ratchet wheel 54 and hence of the number of units of space by 55 which the carriage 10 is shifted for each movement of the lever 56.

As a preliminary to preparing an "original" for the reproduction of sheet music, a sheet of paper 18 bearing stave lines (not shown in the drawings) is first clamped in place upon the rubber facing 17 on the platen 5, by means of the bar 25 and clamping lever 26, and then a scale of unit spaces (not shown) is applied to one of the staves in order to determine into how many 60 unit spaces each stave can be subdivided. The manuscript to be reproduced is then cast up and the number of notes, symbols and signs to be disposed along each stave ascertained; the number of unit spaces allocatable per stave is then 65 divided by the ascertained number of notes, symbols and signs per stave, whereby the average number, together with any surplus, of unit spaces allocatable to each note, symbol or sign is arrived at.

70 The stop 59 is then adjusted in relation to the

stop 58 so that the full extent of angular movement of the lever 56 and hence also of the ratchet wheel 54 is equivalent to such average number of unit spaces allocatable to each individual note, sign or symbol each of which is impressed 5 in turn, by a die stamp 31, in its correct place lengthwise of the stave, by shifting the carriage therealong by moving the lever 56 first clockwise then anti-clockwise in relation to the knurled head 22, the socket 1 being adjusted 10 vertically in relation to the stave lines, as may be necessary, by manipulating the knurled head 9.

As the application to each note impression of the average number of unit spaces would result in a purely mechanical subdivision of the stave 15 irrespective of the correctness of the musical "picture", account must be taken, during the application of the impressions, of the respective musical values of the notes and the artistic interpretation of the theme in order to ensure 20 that the music is set down grammatically correct. For this purpose discretionary additions to or subtractions from the aforesaid average number of unit spaces may be made by manipulation of the pawl and ratchet traversing mechanism 25 accordingly.

What we claim is:

1. Apparatus for preparing, for reproducing by print, originals of music and other printed matter, comprising a support for a plane sheet 30 adapted to receive impressions, and having transverse lines thereon relative to which the printed matter must be positioned accurately, at least one guide socket, an impressing die, said die being adapted to move in a direction perpendicular to said sheet, means for temporarily holding said impressing die in said guide in one position, hand-operated means for pushing said impressing die against said impressing sheet, means for withdrawing said impressing die from 35 said impressing sheet, means for adjusting said guide in a single step transversely of said sheet a predetermined limited number of selected units of space, and means for adjusting said guide longitudinally of said sheet accurately with respect 40 to either said lines or the spaces therebetween, regardless of the position of the guide transversely of said sheet.

2. Apparatus for preparing, for reproducing by print, originals of music and other printed matter, comprising a support for a plane sheet 50 adapted to receive impressions, and having transverse lines thereon relative to which the printed matter must be positioned accurately, at least one guide socket, an impressing die, said die being adapted to move in a direction perpendicular to said sheet, means for temporarily holding said impressing die in said guide in one position, hand-operated means for pushing said impressing die against said impressing sheet, means for withdrawing said impressing die from 55 said impressing sheet, a rack bar extending longitudinally of said sheet and on which bar said guide socket is mounted, the said rack bar having teeth therealong, the pitch of which is equal to the unit distance through which said guide socket is to be moved longitudinally of said sheet, a slide movable transversely of said sheet, a guide along which said slide is movable, a carriage carried on said slide and on which carriage said rack 60 bar is mounted for movement relative thereto, and a spring on said carriage adapted to engage in the space between the teeth of said rack bar.

3. Apparatus for preparing, for reproducing by 70

print, originals of music and other printed matter, comprising a support for a plane sheet adapted to receive impressions, and having transverse lines thereon relative to which the printed matter must be positioned accurately, at least one guide socket, an impressing die, said die being adapted to move in a direction perpendicular to said sheet, means for temporarily holding said impressing die in said guide in one position, hand-operated means for pushing said impressing die against said impressing sheet, means for withdrawing said impressing die from said impressing sheet, a rack bar extending longitudinally of said sheet and on which bar said guide socket is mounted, a member removably mounted on the said rack bar and having teeth therealong, the pitch of which is equal to the unit distance through which said guide socket is to be moved longitudinally of said sheet, a slide movable transversely of said sheet, a guide along which said slide is movable, a carriage carried on said slide and on which carriage said rack bar is mounted for movement relative thereto, and a spring on said carriage adapted to engage in the space between the teeth of said rack bar.

4. Apparatus for preparing, for reproducing by print, originals of music and other printed matter, comprising a support for a plane sheet adapted to receive impressions, and having transverse lines thereon relative to which the printed matter must be positioned accurately, at least one guide socket, an impressing die, said die being adapted to move in a direction perpendicular to said sheet, means for temporarily holding said impressing die in said guide in one position, hand-operated means for pushing said impressing die against said impressing sheet, means for withdrawing said impressing die from said impressing sheet, a rack bar extending longitudinally of said sheet and on which bar said guide socket is mounted, the said rack bar having a first set of teeth along one side thereof and a second set of teeth along the other side thereof, the pitch of which second set of teeth is equal to the unit distance through which said guide socket is to be moved longitudinally of said sheet, a slide movable transversely of said sheet, a guide along which said slide is movable, a carriage carried on said slide and on which carriage said rack bar is mounted for movement relative thereto, a spring on said carriage adapted to engage in the spaces between the said second set of teeth, a rotatably mounted pinion on said carriage meshing with said first set of teeth, and means for rotating said pinion, to move said rack bar relative to said carriage.

5. Apparatus for preparing, for reproducing by print, originals of music and other printed matter, comprising a support for a plane sheet adapted to receive impressions, and having transverse lines thereon relative to which the printed matter must be positioned accurately, at least one guide socket, an impressing die, said die being adapted to move in a direction perpendicular to said sheet, means for temporarily holding said impressing die in said guide in one position, hand-operated means for pushing said impressing die against said impressing sheet, means for withdrawing said impressing die from said impressing sheet, a rack bar extending longitudinally of said sheet and on which bar said guide socket is mounted, the said rack bar having a first set of teeth along one side thereof and a second set of teeth along the other side thereof, the pitch of which second set of teeth is equal to the unit

distance through which said guide socket is to be moved longitudinally of said sheet, a slide movable transversely of said sheet, a second rack bar along which said slide is movable and which has rack teeth along its length, a pinion rotatably mounted in said slide and meshing with the teeth of said second rack bar for adjusting said slide transversely of said sheet, a carriage carried on said slide and on which carriage said first rack bar is mounted for relative movement, a spring on said carriage adapted to engage in the spaces between said second set of teeth, a rotatably mounted pinion on said carriage meshing with said first set of teeth, and means for rotating said last-mentioned pinion, to move said first rack bar relative to said carriage.

6. Apparatus for preparing, for reproducing by print, originals of music and other printed matter, comprising a support for a plane sheet adapted to receive impressions, and having transverse lines thereon relative to which the printed matter must be positioned accurately, at least one guide socket, an impressing die, said die being adapted to move in a direction perpendicular to said sheet, means for temporarily holding said impressing die in said guide in one position, hand-operated means for pushing said impressing die against said impressing sheet, means for withdrawing said impressing die from said impressing sheet, a rack bar extending longitudinally of said sheet and on which bar said guide socket is mounted, the said rack bar having a first set of teeth along one side thereof, and a second set of teeth along the other side thereof, the pitch of which second set of teeth is equal to the unit distance through which said guide socket is to be moved longitudinally of said sheet, a slide movable transversely of said sheet, a second rack bar along which said slide is movable and which has rack teeth along its length, a pinion rotatably mounted in said slide and meshing with the teeth of said second rack bar for adjusting said slide transversely of said sheet, a ratchet wheel fast to the said pinion, a lever rotatable about the axis of said last-mentioned pinion, a detent pivoted on said lever and engaging said ratchet wheel, a spring holding the detent in engagement with said ratchet wheel, a carriage carried on said slide and on which carriage said first rack bar is mounted for relative movement, said lever being pivotally disposed on said carriage, a spring on said carriage adapted to engage in the spaces between said second set of teeth, a rotatably mounted pinion on said carriage meshing with said first set of teeth, and means for rotating said last-mentioned pinion, to move said first rack bar relative to said carriage.

7. Apparatus for preparing, for reproducing by print, originals of music and other printed matter, comprising a support for a plane sheet adapted to receive impressions, and having transverse lines thereon relative to which the printed matter must be positioned accurately, at least one guide socket, an impressing die, said die being adapted to move in a direction perpendicular to said sheet, means for temporarily holding said impressing die in said guide in one position, hand-operated means for pushing said impressing die against said impressing sheet, means for withdrawing said impressing die from said impressing sheet, a rack bar extending longitudinally of said sheet and on which bar said guide socket is mounted, the said rack bar having a first set of teeth along one side thereof, and a second set of teeth along the other side thereof,

the pitch of which second set of teeth is equal to the unit distance through which said guide socket is to be moved longitudinally of said sheet, a slide movable transversely of said sheet, 5 a second rack bar along which said slide is movable and which has rack teeth along its length, a pinion rotatably mounted in said slide and meshing with the teeth of said second rack bar for adjusting said slide transversely of said sheet, 10 a ratchet wheel fast to the said pinion, a lever rotatable about the axis of said pinion, a detent pivoted on said lever and engaging said ratchet wheel, a spring holding the detent in engagement with said ratchet wheel, an arm pivoted on said lever and bearing against one end 15 of said detent for moving the detent out of engagement with said ratchet wheel when desired, a carriage carried on said slide and on which carriage said first rack bar is mounted for relative movement, said lever being pivotally disposed on 20 said carriage, a spring on said carriage adapted to engage in the spaces between said second set of teeth, a rotatably mounted pinion on said carriage meshing with said first set of teeth, and means for rotating said last-mentioned pinion, 25 to move said first rack bar relative to said carriage.

8. Apparatus for preparing, for reproducing by print, originals of music and other printed matter, comprising a support for a plane sheet adapted to receive impressions, and having transverse lines thereon relative to which the printed matter must be positioned accurately, at least one guide socket, an impressing die, said die being adapted to move in a direction perpendicular to said sheet, means for temporarily holding said impressing die in said guide in one position, hand-operated means for pushing said impressing die against said impressing sheet, means for withdrawing said impressing die from said impressing sheet, means for adjusting said guide in a single step transversely of said sheet a predetermined limited number of selected units of space, and means for adjusting said guide longitudinally of said sheet accurately with respect to either said lines or the spaces therebetween, regardless of the position of the guide transversely of said sheet, a rack bar extending longitudinally of said sheet and on which bar said guide socket is mounted, the said rack bar having a first set of teeth along one side thereof, and a second set of teeth along the other side thereof, the pitch of which second set of teeth is equal to the unit distance through which said guide socket is to be moved longitudinally of said sheet, a slide movable transversely of said sheet, a second rack bar along which said slide is movable and which has rack teeth along its length, a pinion rotatably mounted in said slide and meshing with the teeth of said second rack bar for adjusting said slide transversely of said slide, a ratchet wheel fast to the said pinion, a lever rotatable about the axis of said last-mentioned pinion, a detent pivoted on said lever and engaging said ratchet wheel, a spring holding the detent in engagement with said ratchet wheel, a second stop threaded through said slide, the said stops being disposed in the path of said lever and limiting the movement thereof, a carriage carried on said slide and on which carriage said first rack bar is mounted for relative movement, said lever being pivotally disposed on said carriage, a spring on said carriage adapted to engage in the spaces between said second set of

teeth, a rotatably mounted pinion on said carriage meshing with said first set of teeth, and means for rotating said last-mentioned pinion, to move said first rack bar relative to said carriage.

9. Apparatus for preparing, for reproducing by print, originals of music and other printed matter, comprising a support for a plane sheet adapted to receive impressions, and having transverse lines thereon relative to which the printed matter must be positioned accurately, at least one guide socket, an impressing die, said die being adapted to move in a direction perpendicular to said sheet, means for temporarily holding said impressing die in said guide in one position, hand-operated means for pushing said impressing die against said impressing sheet, means for withdrawing said impressing die from said impressing sheet, a rack bar extending longitudinally of said sheet and on which bar said guide socket is mounted, the said rack bar having a first set of teeth along one side thereof, and a second set of teeth along the other side thereof, the pitch of which second set of teeth is equal to the unit distance through which said guide socket is to be moved longitudinally of said sheet, a slide movable transversely of said sheet, a second rack bar along which said slide is movable and which has rack teeth along its length, a pinion rotatably mounted in said slide and meshing with the teeth of said second rack bar for adjusting said slide transversely of said sheet, a ratchet wheel fast to, but removable from the said pinion, a lever rotatable about the axis of said last-mentioned pinion, a detent pivoted on said lever and engaging with said ratchet wheel, a spring holding the detent in engagement with said ratchet wheel, a carriage carried on said slide and on which carriage said first rack bar is mounted for relative movement, said lever being pivotally disposed on said carriage, a spring on said carriage adapted to engage in the spaces between said second set of teeth, a rotatably mounted pinion on said carriage meshing with said first set of teeth, and means for rotating said last-mentioned pinion, to move said first rack bar relative to said carriage.

10. Apparatus for preparing for reproducing by print, originals of music and other printed matter, comprising a support for a plane sheet adapted to receive impressions and having transverse lines thereon relative to which the printed matter must be positioned accurately, a plurality of guide sockets, an impressing die, said die being adapted to move in a direction perpendicular to said sheet, means for temporarily holding said impressing die in a selected one of said guides in one position, hand-operated means for pushing said impressing die against said impressing sheet, means for withdrawing said impressing die from said impressing sheet, a rack bar extending longitudinally of said sheet and on which bar said guide sockets are mounted so as to be movable and adjustable relative to each other, the said rack bar having teeth therealong, the pitch of which is equal to the unit distance through which said guide socket is to be moved longitudinally of said sheet, a slide movable transversely of said sheet, a guide along which said slide is movable, a carriage carried on said slide and on which carriage said rack bar is mounted for movement relative thereto, and a spring on said carriage adapted to engage in the space between the teeth of said rack bar.
